CLAIM

We claim the ornamental design for a planting system carrying device, as shown and described.

DESCRIPTION

FIG. 1 depicts a perspective view of a planting system carrying device.

FIG. 2 is a rear elevational view thereof.

FIG. 3 is a front elevational view thereof.

FIG. 4 is a right side elevational view thereof.

FIG. 5 is a left side elevational view thereof.

FIG. 6 is a top plan view thereof.

FIG. 7 is a bottom plan view thereof.

FIG. 8 is a front perspective view thereof in a second position of use; and,

FIG. 9 is a rear perspective view thereof in a second position of use.

The broken lines on the tabs arranged about each of the openings illustrate perforation and form part of the claimed design.
